SPRING STABILIZER

Raymond H. Lee and Perry A. Lee, both of
404 S. Gossett St., Anderson, S.C.
Filed Sept. 17, 1959, Ser. No. 840,762
1 Claim. (Cl. 139—270)

The present invention relates to a loom, and more particularly to an improved filling feeler for such a loom.

This invention is an improvement over the filling feeler shown and described in our prior Patent 2,705,026.

This invention has as an object the provision of a means for stabilizing the filling feeler so as to cause the filling feeler to operate more efficiently or satisfactorily.

This invention has as a further object the provision of an improved filling feeler which will prevent injury to the yarn and wherein a means is provided for stabilizing the actuating rod so as to insure that the device will operate in a highly advantageous and satisfactory manner.

Another object of the present invention is to provide a filling feeler which is simple in construction, easy to adjust, easy to operate, well adapted for its intended purposes, and relatively inexpensive to manufacture, and install.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a view illustrating certain constructional details of the present invention.

FIGURE 2 is a sectional view showing the spring which is mounted on the actuating rod.

FIGURE 3 is a view taken at right angles to the view shown in FIGURE 2.

Referring in detail to the drawings, the numeral 10 indicates a portion of a conventional shuttle which has thereon the usual bobbin 11. The numeral 12 indicates yarn or filling on the bobbin 11, and there is also provided a slot or cutout portion 14 in the shuttle 10, as shown in the drawings, and as shown in our prior Patent 2,705,026.

The numeral 15 indicates the case or feeler housing having a slot 16 and the numeral 17 indicates the filling feeler which embodies the shank 18 as well as a feeler tip 19 on one end thereof, and the tip 19 is adapted to engage the yarn or bobbin in the shuttle 10, there being a transversely arranged arm 20 on the inner end of the shank 18. The numeral 21 indicates a coil spring which has one end connected to the arm 20, and the other end of the coil spring 21 is anchored to the housing 15, as at 22. The numeral 23 indicates a stop shoulder in the housing 15 for engagement with the end of the arm 20, and the numeral 24 indicates an actuating rod or wire which has a portion thereof arranged at right angles with respect to the shank 18.

According to the present invention there is provided a bracket 25 which includes a main body portion 26 which is affixed to the housing 15 as at 27. The outer end of the bracket 25 includes a right angularly arranged flange 28 provided with an aperture 29 therein, and the rod 24 extends through the aperture 29 in the flange 28. The numeral 30 indicates a collar which is mounted on the rod 24, and a coil spring 31 is circumposed on the rod 24, the coil spring being interposed between the bushing 30 and the flange 28.

The collar 30 is adjustable on the rod 24 so that the tension from the spring 31 can be varied or regulated as desired. Thus, a securing element such as a set screw 32 extends through the collar 30 and engages the rod 24,

2

so that by loosening the set screw 32, the collar 30 can be moved to any desired position on the rod 24, so as to provide a means for varying or regulating the tension of the spring 31. After the collar 30 has been moved to the desired location, the element 32 is tightened so as to maintain the parts immobile in their desired positions.

From the foregoing, it is apparent that there has been provided a filling feeler which is an improvement over the filling feeler shown and described in our prior Patent 2,705,026. It is to be noted that the feeler tip is arranged so that when there is sufficient material 12 on the bobbin 11, the material 12 strikes the feeler tip 19 so that the rod 24 will not be moved but when the supply 12 becomes substantially exhausted, the tip 19 will be struck by the bobbin 11 and will slide along the bobbin to move the rod 24 and this movement of the rod 24 serves to start the operation of the bobbin changing mechanism in order to control the filling replenishing mechanism of the loom.

The bobbin can be changed even before the yarn has become completely exhausted and when there is yarn 12 on the bobbin 11, the feeler tip 19 causes the feeler 17 to push back the casing 15 in such a manner as to prevent the filling feeler from engaging the rod 24 to set the replenish mechanism in motion. When all of the filling 12 is exhausted from the bobbin 11, the feeler will work in the same manner as conventional feelers so that the tip 19 can slide on the empty bobbin.

It is to be understood that the present invention embodies or includes a stabilizing of the actuating rod 24 as well as the lifting lever. In the improved filling feeler of the present invention there is provided a metal strap or bracket 25 as well as the collar 30 and the spring 31 and the purpose of these members is to stabilize the filling feeler which should be driven straight back by the bobbin 35 until the yarn is exhausted, but allowing the side motion of the feeler to engage the actuating rods so as to cause the filling motion to function.

In our prior Patent 2,705,026 the feeler is held rigid and the bobbin occasionally moves slightly sideways so as to injure the yarn. The improved feeler attachment of the present invention will allow the slight side movement without injuring the yarn and it is also less expensive because the entire feeler on most looms can be used by adding the stabilizing attachment only and this would be much less costly to the purchaser.

As the tip 19 strikes the quill or member 11, then on forward movement of the shuttle 10, the feeler tip 19 will engage the filling on the bobbin and if the bobbin moves slightly in the shuttle, as has been observed in the past, the tip 19 will move slightly in the direction away from the rod 24, free of compressive forces of the spring 31, without damaging the filling, and will be permitted to move in the lateral direction toward the rod 24 against the compressive forces of the spring 31.

The force of the spring 31 is easily adjusted by shifting the collar 30 so that the feeler tip can shift slightly laterally in each direction with the bobbin, but upon exhausting of the bobbin the tip will slide laterally on the bobbin bare portion to actuate the rod to the bobbin change mechanism so as to automatically kick-out the empty bobbin and replace it with a full bobbin. Heretofore with the old style conventional device, when the bobbin was kicked-out by the filling mechanism, often too much material remained on the bobbin which is wasteful but the present invention will overcome this disadvantage.

Minor changes in shape, size and rearrangement of details coming within the field of invention claimed may be resorted to in actual practice if desired.

We claim:

In a loom feeler mechanism including a case mounted for movement toward and away from a shuttle when said

shuttle is in the loom shuttle box, a filling feeler having a shank projecting loosely through one wall of said case, said shank having a tip on the end externally of said case adapted to engage the filling on a bobbin in said shuttle responsive to movement of said case toward said shuttle, and a shuttle replenishing mechanism actuating rod extending slidably into said case, said rod having said one end abuttingly engagable by said feeler shank responsive to lateral movement in one direction of said shank upon slippage of said tip along a bare portion of said bobbin 10 when engaged, the improvement consisting in a spring circumscribed about the portion of said rod adjacent to and exteriorly of said case and connected to said case so as to bias said rod into engagement of said rod end with the portion of said shank within said casing whereby said shank portion is laterally movable in said one direction 15 against the compressive forces of said spring and is

4
laterally movable in the other direction free of compressive forces of said spring.
